EGG TRAY

Arthur W. Theilig, Fort Atkinson, Wis., assignor to Rockwood & Co., Chicago, Ill., a corporation of Delaware

Filed Aug. 11, 1961, Ser. No. 66,304

Term of patent 14 years

(Cl. D58—13)

FIG. 1 is a top perspective view of an egg tray embodying my new design.

FIG. 2 is a bottom perspective view thereof.

FIG. 3 is an enlarged fragmentary top plan view showing one corner thereof.

FIG. 4 is a fragmentary side view of the egg tray of FIG. 1.

FIG. 5 is a cross section taken along the line 5—5 of FIG. 3.

FIG. 6 is a cross section taken along the line 6—6 of FIG. 3.

I claim:

The ornamental design for an egg tray, as shown.
